R. M. MAJOR.
CYANID FURNACE.
APPLICATION FILED FEB. 17, 1920.

Harlett / Muncey.

UNITED STATES PATENT OFFICE.

RALPH MARSHALL MAJOR, OF BLOOMFIELD, NEW JERSEY, ASSIGNOR TO DRIVER-HARRIS COMPANY, OF HARRISON, NEW JERSEY, A CORPORATION OF NEW JERSEY.

CYANID-FURNACE.

1,387,286.

Specification of Letters Patent. Patented Aug. 9, 1921.

Application filed February 17, 1920. Serial No. 359,280.

To all whom it may concern:

Be it known that I, RALPH MARSHALL MAJOR, a citizen of the United States, residing at Bloomfield, county of Essex, and 5 State of New Jersey, have invented a certain new and useful Improvement in Cyanid-Furnaces, of which the following is a full, clear, and exact description.

My invention relates to improvements in 10 cyanid furnaces and has for its object to provide a furnace of which the pot shall have a much longer life than pots in furnaces now in use, and in which the furnace itself shall also have a longer life than furnaces now in use. It further has for its 15 object to produce a cyanid furnace in which there should be a smaller loss of cyanid by volatilization, also a furnace in which the hood shall have a longer life and afford 20 greater protection to workmen, also a furnace which will result in a reduction of the damage due to escaping cyanid fumes.

One feature of my invention consists in 25 forming a seal between the hood and the pot, so as to substantially prevent any cyanid from the pot reaching the interior of the furnace. Another feature consists of separate flues leading from the fire chamber and hood respectively. Another feature 30 of my invention consists in the use of a pot formed of an alloy comprising nickel and chromium in connection with a sealed hood and separate fire chamber flue.

In cyanid furnaces as heretofore constructed, the linings have been of ordinary 35 silicious fire-brick, and the pot has been made of cast iron having a flange supported by the upper course of bricks forming the lining, a suitable hood being provided to 40 which a flue is connected, through which hood and flue the products of combustion from the fire chamber are discharged, and which flue also serves to carry off the unsublimated cyanid vapors. Such iron pots 45 have comparatively short life, and when they are destroyed not only is it necessary to renew the pot but it is also necessary to re-line the furnace. When a pot made of a refractory alloy comprising nickel and chromium 50 is substituted for an iron pot, the life of the substituted pot is somewhat longer, but not sufficiently longer to justify the additional expense. I have discovered that

this is largely due to the fact that cyanid from the pot works back into the fire chamber by dropping through the flue or trickling beneath the rim of the pot so that, in conjunction with the products of combustion or heat, some very active agent is produced which attacks the exterior of the pot 55 and also the silicious lining of the fire chamber, and have invented a furnace in which the cyanid from the pot can be substantially excluded from the fire chamber so as to increase the life of the pot and the furnace 60 65 lining.

I have further discovered that by separating the cyanid fumes from the products of combustion in my improved furnace the cyanid vapors are much less highly heated 70 and, coming in contact with the walls of the hood which are kept cool by the surrounding air, are sublimated to a very considerable extent so that they are largely returned to the pot instead of passing off 75 through the stack with the products of combustion. The hood being less highly heated lasts longer and is more easily approached by the workmen.

The furnace has various other features of 80 advantage which will be hereinafter more particularly pointed out.

The following is a description of an embodiment of my invention, reference being had to the accompanying drawings, in 85 which,

Figure 1 shows a vertical section through the furnace embodying my invention;

Fig. 2 is a section on the line 2—2, Fig. 1;

Fig. 3 is a vertical section of a modified 90 form of furnace embodying my invention, and

Fig. 4 is a horizontal section of the same on the line 4—4, Fig. 3.

Referring more particularly to the drawings, 1 is a furnace body having a lining 2 of ordinary fire-brick, which, as is well known, is a brick containing silicious material, forming a fire chamber 3.

This furnace is preferably heated by an 100 oil burner 4 extending into an opening in the furnace wall, so as to heat the pot 5 suspended from the upper end of the furnace wall. This pot 5 is made of a refractory alloy comprising nickel and chromium. 105 The particular alloy which I prefer to use

also contains iron. While the proportions may be considerably varied, the composition is preferably about as follows:

5	Nickel-----	60	per cent.
	Chromium-----	12	" "
	Iron-----	26	" "
	Manganese-----	1.5	" "

6 is a sheet iron hood having a door 7 through which articles to be treated can be introduced to the pot 5 or removed therefrom. To the upper part of this hood is connected a stack 8, which discharges any cyanid vapors which may be created and are not sublimated. In order to provide a seal between the pot and the hood, I may form upon the pot an extension 9, having a sloping surface and an upwardly extending flange 10, within which the bottom of the hood 6 fits, so as to form a seal which will substantially prevent the escape at that point of cyanid and so that no cyanid vapors or material can escape and find their way back into the interior of the furnace. 20 The fire chamber of the furnace is provided with a flue 11, which is entirely separated from the space above the pot 5 and the hood 6 and acts to discharge the products of combustion of the fire chamber into the 30 external atmosphere.

The form shown in Fig. 3 is the preferred form. It is similar to the others except that the pot 5' is of ordinary form, having a horizontal flange 12 and the upper course 35 of the furnace wall 13 is made of some neutral material, such as a tamped layer of chrome ore, above which is placed a seal 14 of basic material sloping downward toward the interior of the pot 5. The seal 14 acts 40 to close the space between the hood and the flange 12, so as to prevent the downward passage of any melted or vaporized cyanid at that point. The sloping surface referred to guides any cyanid which may be sublimated within the hood into the pot. 45

In both of these forms all or substantially all cyanid within the pot is prevented from ever entering the fire chamber of the furnace, with the result that the exterior of 50 the pot is never subjected to the action of the destructive gases which would be produced by the entrance of the cyanid into the fire chamber, and so that the inner walls of the furnace are also never subjected to such 55 action. By the exclusion of the cyanid from the fire-chamber the life of the pot is greatly extended and the life of the furnace lining is also greatly extended. This substantial exclusion of the cyanid from the pot is 60 brought about by the provision of a separate and independent flue for the products of combustion, as distinguished from the use of a single flue to discharge both the cyanid fumes from the hood and the products 65 of combustion, which use heretofore

prevented cyanid working backward into the fire-pot, and also by the provision of a seal between the hood and a fire-pot, which will prevent cyanid from working into the fire chamber by passing beneath the flange of 70 the pot.

In the furnace of Figs. 3 and 4, the basic seal 14 is preferably of tar, slag and magnesite molded and tamped into place. This being basic is not attacked by the cyanid. 75 It is necessary, however, to separate the basic seal from the acid fire-bricks with which the furnace is lined, since otherwise one would act upon the other in the presence of the intense heat of the furnace. This 80 separation is attained by the layer of chrome ore which is so neutral as not to be affected by either the basic or acid materials contacting therewith.

By using the chrome ore or other neutral 85 separator the furnace can be lined with ordinary fire-brick as distinguished from the more expensive magnesite or other basic brick which would otherwise be necessary if the furnace lining contacted with a basic 90 seal.

The cyanid bath used is the ordinary or commercial bath commonly employed, 76% sodium cyanid and 24% sodium chlorid.

As will be evident to those skilled in the 95 art, my invention permits of various modifications without departing from the spirit thereof or the scope of the appended claims.

What I claim is:

1. The combination of a refractory cyanid pot, a furnace for heating the same, a hood for said pot substantially preventing cyanid from said pot entering the interior of said furnace, a flue for said hood and a flue for the products of combustion of said furnace independent of said hood and its flue. 100 105

2. The combination of a refractory cyanid pot, a furnace for heating the same, a hood for said pot substantially preventing cyanid from said pot entering the interior of said furnace, a flue for said hood, a flue for the products of combustion of said furnace independent of said hood and its flue, and a basic seal between said hood and said pot. 110 115

3. The combination of a refractory cyanid pot, a furnace for heating the same, a hood for said pot substantially preventing cyanid from said pot entering the interior of said furnace, a flue for said hood, a flue for the products of combustion of said furnace independent of said hood and its flue, said furnace having a wall composed of acid materials, a basic seal between said hood and said pot, and a neutral layer between said seal and said furnace wall. 120 125

4. The combination of a refractory cyanid pot, a furnace for heating the same, a hood for said pot substantially preventing 130

cyanid from said pot entering the interior of said furnace, a flue for the products of combustion of said furnace independent of said hood, and a basic seal between said 5 hood and said pot, said seal having a surface sloping toward the pot.

5. The combination of a refractory cyanid pot, a furnace for heating the same, a hood confining the fumes from said pot so 10 as to substantially prevent the cyanid from said furnace entering the fire chamber of said furnace, said hood being exposed to a cooling medium and acting to sublimate cyanid fumes rising from said pot, and a flue 15 for the products of combustion of said furnace independent of said hood.

6. The combination of a refractory cyanid pot, a furnace for heating the same, a

hood for said pot substantially preventing cyanid from said pot entering the interior 20 of said furnace, a flue for said hood, and a flue for the products of combustion of said furnace independent of said hood and its flue, said pot being composed of an alloy comprising chromium.

25 7. The combination of a refractory cyanid pot, a furnace for heating the same, a hood for said pot substantially preventing cyanid from said pot entering the interior 30 of said furnace, a flue for said hood and a flue for the products of combustion of said furnace independent of said hood and its flue, said pot being composed of an alloy comprising nickel and chromium.

RALPH MARSHALL MAJOR.
